Primary Examiner — George D. Kirschbaum*Assistant Examiner* — Darcey E Heflin(74) *Attorney, Agent, or Firm* — 3M Innovative Properties Company; Trisha D. Adamson(57) **CLAIM**

The ornamental design for a medical dressing, as shown and described.

DESCRIPTION

FIG. 1 is a perspective view of the new design for a medical dressing;

FIG. 2 is a top plan view thereof;

FIG. 3 is a bottom plan view thereof;

FIG. 4 is a right side view elevational view thereof;

FIG. 5 is a left side elevational view thereof;

FIG. 6 is a front elevational view thereof; and,

FIG. 7 is a back elevational view thereof.

In the drawings, the broken lines show portions of a medical dressing that form no part of the claim. In addition, the surface shading illustrated in the drawings is provided merely to highlight the contour of design; it is not intended to be illustrative of texture or gloss.
